EXPANSIBLE PLUG FOR CEMENTING WELLS

H. R. Steward, Lohn, Tex.

Application February 4, 1949, Serial No. 74,508

3 Claims. (Cl. 166—13)

1

This invention relates to apparatus for cementing wells, and more particularly to an expandable plug which can be positioned in a well to temporarily seal off a lower portion of the well while cement is being applied to a portion of the well immediately above the plug.

It is among the objects of the invention to provide a collapsible plug which may be lowered through a well casing or lining to a desired position below the bottom end of the casing and there expanded into sealing engagement with the wall of the well to hold cement pumped into the well and prevent such cement from passing below the plug to a location where it might interfere with the flow of valuable material into the well, which plug is firmly supported at the desired level and is automatically expanded into sealing engagement with the wall of the well, is simple and economical in construction and readily destructible by a drill bit so that the well can be quickly and easily re-opened after the cementing operation is completed, and so that the use of the expandable plug does not add materially to the cost of cementing a well, which plug is easily variable for different well sizes and different conditions of the walls of different wells, and may be used with conventional well-drilling and cementing equipment.

Other objects and advantages will become apparent from a consideration of the following description and the appended claims in conjunction with the accompanying drawing, wherein:

Figure 1 is a somewhat diagrammatic, longitudinal cross-section of the lower portion of a well showing a well casing therein and an expandable plug illustrative of the invention positioned in the well below the bottom end of the casing, a bottom portion of the casing and a portion of the plug being broken away and shown in cross-section to better illustrate the construction of the plug and the cooperation thereof with the well and well casing;

Figure 2 is a top plan view of the plug in expanded condition; and

Figure 3 is a transverse cross-section of a well casing showing therein a top plan view of the expandable plug in collapsed condition for passing through the casing.

With continued reference to the drawing, the well hole is illustrated as having a somewhat irregular wall 10 extending outwardly into basins 11 somewhat above the bottom 12 of the well, which basins are located at the level of valuable material, such as oil, gas, brine or water, which it is desired to remove through the well. The

2

well lining or casing 13 is somewhat smaller in diameter than the well bore and terminates above the basins 11 from which the valuable material flows into the well. A screw-threaded union fitting 14 may be secured on the bottom end of the casing, if desired.

The expandable plug is generally indicated at 15, and comprises an elongated post or column 16, the bottom end of which rests upon the bottom 10 of the well when the plug is in operative position, and the upper end of which is positioned between the basins 11 at the level of the valuable material and the bottom end of the well casing 13 and near the bottom end of the well casing. 15 The length of the post 16 is predetermined by drilling measurements of the well and the post is cut to the proper length before the expandable plug is lowered to the bottom of the well through the well casing. A polygonal plate 17 substantially concentric with the post 16 and perpendicular to the longitudinal center-line of the post is provided on the upper end of the post either permanently attached to or formed integrally with the latter. The edges of the polygonal plate 20 17 are provided with respective pairs of spaced-apart hinge eyes or loops 18, and a number of wing plates 19 equal to the number of straight edges of the polygonal plate 17 are secured respectively to the straight edges of the polygonal plate 25 for movement inwardly and outwardly about such pivotal or hinged connections. 30

Each of the wing plates 19 is trapezoidal in form and has on its shortest edge a hinge loop 20 disposed between the hinge loops 18 on the corresponding edge of the polygonal plate 17 to receive a hinge pin extending through the cooperating hinge loops. Each wing plate 19 preferably has beveled side edges and may be curved or dished near its outer end to somewhat more closely conform to the cylindrical shape of the well bore.

In placing the expandable plug in operating position at the bottom of the well casing, as illustrated in Figure 1, the wing plates are swung inwardly to their collapsed condition, as illustrated at 13, and the plug is placed in the top of the well casing. It is then allowed to drop through the well casing or may be forced downwardly through the casing by the application of suitable weight, such as a string of drill stem sections, if necessary.

A pair of elongated, curved leaf springs 21 is secured at adjacent ends to the polygonal plate 17, substantially at the center of the latter, by a suitable clip 22, and bears against some of the

wing plates, for example, the three wing plates constituting the inner triangle illustrated in Figure 3, to resiliently force the wing plates outwardly to their expanded position as soon as these plates drop below the bottom end of the well casing. The spring forces the wing plates outwardly until their outer edges contact the wall of the well bore, so that these plates make a seal with the well bore immediately below the bottom end of the well casing. If the casing is merely suspended in the well bore at this time, it may be lowered sufficiently to contact these wing plates and force them into firmer engagement with the wall of the well bore. With the plug in operative, expanded condition, as illustrated in Figure 1, cement may be poured or pumped through the well casing to cement the well, and will not pass below the level of the wing plates 19 of the expandable plug.

The trapezoidal wing plates 19 may be provided in any desired or necessary number, depending upon the shape of the polygonal plate 17, and may be provided in sets of different lengths to accommodate the plug to wells of different sizes, or to varying conditions of the walls of different well bores, so that a firm seal can be provided immediately below the bottom end of the well casing regardless of the size of the well or the condition of its walls.

After the cementing of the well has been completed, the plug may be destroyed by action of a drill bit thereon, and for this purpose the material of the plug should be considerably softer than the material of which drill bits are conventionally made.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A well cementing expandable plug comprising an elongated post having on one end a plate of polygonal formation, and a plurality of wing plates of substantially trapezoidal formation each hinged along its shortest edge to a respective edge of said polygonal plate so that said wing plates can swing inwardly and outwardly between a col-

lapsed and an expanded condition of said plug, and curved, leaf springs mounted on said polygonal plate and bearing against some of said wing plates to resiliently urge said wing plates outwardly about their hinge connections with said polygonal plate.

2. A well cementing expandable plug comprising a post of predetermined length to rest upon the bottom of a well and position its upper end at a desired level for cementing the well, a polygonal plate on the upper end of said post substantially concentric with the latter, a number of trapezoidal wing plates equal to the number of straight edges of said polygonal plate, a hinge connection between each straight edge of said polygonal plate and the shortest edge of the corresponding wing plate, said wing plates being movable about said hinge connections between a collapsed condition in which said plug will pass through a well casing and an expanded condition in which the outer edges of said wing plates will contact the wall of a well bore below the associated well casing, and spring means carried on said polygonal plate and bearing against said wing plates to resiliently urge said wing plates outwardly to expanded condition.

3. A well cementing expandable plug comprising a post of predetermined length to rest upon the bottom of a well and position its upper end at a desired level for cementing the well, a plurality of trapezoidal wing plates, hinge connections respectively connected between the shortest edges of said wing plates and the top of said post, said wing plates being movable about said hinge connections between a collapsed condition in which said plug will pass through a well casing and an expanded condition in which the outer edges of said wing plates will contact the wall of a well bore below the associated well casing, and spring means carried on the top of said post within said wing plates and bearing against said wing plates to resiliently urge said wing plates outwardly to expanded condition.
